UNITED STATES PATENT OFFICE.

GEORGE WILSON BLAKESLEE, OF PERRY, IOWA.

SELF-BINDING HARVESTER.

SPECIFICATION forming part of Letters Patent No. 350,969, dated October 19, 1886.

Application filed November 19, 1885. Serial No. 183,322. (No model.)

To all whom it may concern:

Be it known that I, GEORGE WILSON BLAKESLEE, a citizen of the United States, residing at Perry, in the county of Dallas and 5 State of Iowa, have invented certain new and useful Improvements in Self-Binding Harvesters; and I do hereby declare the following to be a full, clear, and exact description of the invention, such as will enable others skilled 10 in the art to which it appertains to make and use the same.

This invention relates to self-binding harvesters; and the object of the invention is to provide this class of harvesters with novel 15 means for binding with twine, and for automatically tying the knot in the band, and for dropping the sheaf.

To this end my invention consists in the construction and combination of parts forming 20 a knot-tyer, hereinafter described and claimed, reference being had to the accompanying drawings, in which—

Figure 1 is a longitudinal vertical section, part in elevation, of a portion of a harvester, 25 showing my invention attached thereto. Fig. 2 is a front elevation of a portion of the same. Fig. 3 is a side elevation of the principal parts of the knotting device which are below the binding-table; and Fig. 4 is an inverted plan 30 view of the same above the section-line *x x*, Fig. 3. Fig. 5 is a detail view showing parts of Fig. 3, bearing the same numbers, from the opposite side. Fig. 6 is an inverted plan view of a portion of the knotting device, taken at 35 the section-line *y y*, Fig. 3. Fig. 7 is a front elevation of part of the sheaf-dropping device, and Fig. 8 is a sectional side elevation of the same. Fig. 9 is a sectional elevation of the knotter, showing the needle in 40 cross section. Fig. 10 is a central vertical longitudinal section of the knotter, showing the cord-holder and portions of adjacent parts. Fig. 11 is a horizontal section of a portion of the cord-holder at line *w*, Fig. 10, showing adjacent parts in plan. Fig. 12 is a horizontal 45 section of the knotter-shaft, showing its appendages at line *z z*, Fig. 10. Fig. 13 is a horizontal section of the knotter-shaft, showing some adjacent parts at line *v v*, Figs. 3 and 50 10. Fig. 14 is a side elevation of the knotter. Fig. 15 is a plan view of the looper, showing a portion of the cord-holder in horizontal sec-

tion. Fig. 16 is a plan view of the looper at a different stage of action, showing the knife in horizontal section. Fig. 17 is a transverse 55 vertical section at *t t*, Fig. 1. Fig. 18 is a plan view of a portion of a harvesting-machine, showing the invention on a slightly-reduced scale. Fig. 19 is a horizontal section of the looper-shaft at *q q*, Fig. 10. Fig. 6c 20 is a transverse vertical section of the twine-cutter at the line *x x*, Fig. 4.

In order that my knot-tyer may be fully understood, I find it necessary to show in the accompanying drawings some of the accessories thereto, such accessories being only generally described herein. The self-binding harvester, of which portions are shown, was patented to me August 18, 1885, No. 324,524, application filed March 4, 1884, and this application covers matter eliminated therefrom, 70 which the applicant therein expressed an intention to apply for subsequently.

A represents the drive-wheels, rigidly secured upon the axle B, which is journaled to 75 revolve in bearings of the frame C, and D represents the bed of a harvesting-machine. Upon this bed the grain falls in the process of cutting, and it may be carried thence to the binding-table E by any suitable mechanism 80 which will force a gavel against the binding-twine F and form a bight in the latter, after which the descent of the needle H completes the binding-loop, as shown in Fig. 17 partly in dotted lines. The ball or spool of twine is 85 carried in a box, G, which is secured upon the frame of the machine. The twine is passed from the box G through guide-eyes *G' G''* to a groove in the back of the needle H, which groove it follows to the eye *H'* of the needle, 90 from which it extends across the path of the incoming gavel to the crown-wheel I, which is a portion of the keeper, whereby its end is held, a spring-clamp, I', acting in conjunction with the said crown-wheel for that purpose. 95 Any common tension device may be used to keep the twine tight. The gavel being in the bight of the twine, the latter is closed around it to form a complete band by the needle H swinging from the position shown in dotted 100 lines, Fig. 17, to the position shown in full lines. The needle H is a curved radial arm, its outer part forming an arc of a circle, and it is fixed at one end of its arm at a point

nearly concentric with the said are upon a rock-shaft, H^2 , which is journaled in posts H^3 that are fixed at their lower ends to the frame of the machine.

5 H^4 is an arm fixed to and projecting from the rock-shaft H^2 through the loop of a cam-lever, J , which is fixed on one end of a rock-shaft, J' , that is journaled in bearings J^2 , one of which projects from the main frame and the 10 other from one of the posts H^3 .

J^3 is an arm fixed to and depending from the other end of the rock-shaft J' , and connected by a rod, J^4 , with a cam, J^5 , which is mounted loosely on the shaft K , so that the shaft may 15 revolve without revolving the cam. This cam is provided at one end with clutch-teeth to be engaged by a clutch, K' , which is splined to the shaft K , so as to be forced to revolve therewith and yet be free to slide longitudinally 20 thereon enough to engage or disengage the teeth of the cam.

K^2 is a spur-wheel fixed upon the shaft K and engaged by a pinion, K^3 , which is splined to a shaft, K^6 , and provided with a neck, K^7 , 25 whereby the said spur-wheel may be engaged by a hand-lever to be slid endwise upon the shaft K^6 to engage or disengage the spur-wheel K^2 .

K^4 is a pinion rigidly fixed upon the shaft 30 K^6 to engage a spur-wheel, K^5 , that is fixed to the inner face of one of the drive-wheels A .

To cause the knot-tyer to operate, the wheels K^2 and K^3 are kept engaged, whereby the advance of the machine, causing the wheels A 35 K^5 to revolve, produces rotary motion in the train of wheels K^4 K^3 K^2 and the clutch K' , so that they run continuously, thereby keeping in operation the various parts of the knot-tyer which are connected therewith, as before described.

29 represents a series of fingers loosely hung upon the needle-shaft H^2 , slantingly to the table E , across the path of the incoming grain, to be gradually raised thereby. The shifter 40 35 is engaged at one end with the groove in the clutch K' , and is rigidly hung by the other end to a rock-shaft, 31, which is journaled in posts of the main frame and provided with a long-wristed crank, 30, that rides upon the fingers 29. When enough grain has been 45 gathered to form a full sheaf, the fingers 29 and crank 30 have been thereby raised to the height which causes the shifter 35 to move the clutch K' into engagement with the cam J^5 , which at one revolution first drives the rod J^4 50 forward to the right in Fig. 1, thereby depressing the cam-lever J , and with it the needle H , and carrying a bight of the twine F to a position to be united with its opposite end by 55 the looper, and then returns these parts to their starting-point, when the clutch K' is disengaged from the cam by a device hereinafter described, leaving the needle, &c., waiting for another gavel to be gathered. The crown-wheel I is inverted and pivoted centrally to the under side of the table E , its downward-faced scallops serving as teeth to carry the

twine between the jaws of the clamp I' . This clamp is formed of a piece of spring metal, 70 arched and straddling the edge of the crown-wheel and springing toward it to hold the twine thereto. The said clamp is fixed to the table E a little to one side of the path of the needle H , Figs. 10 and 11.

80 represents a ratchet-wheel rigidly secured 75 on top of the crown-wheel I , and 81, Fig. 4, represents a detent provided with a spring, 82, to hold the crown-wheel from being turned backward when the twine held thereby is pulled upon in tying the knot.

83 is a pawl engaging at one end the teeth 80 of wheel 80, and pivoted near the other end to a lever, 87, which is pivoted midway to the under side of the binding-table E .

84 is a roller mounted in the rear end of the 85 pawl 83, to travel upon a curved plate, 85, which is pivoted to the table E , and is constantly pressed toward the roller by a spring, 86. By this means the pawl 83 is kept against the wheel 80 throughout the movement of the 90 driving-lever 87, and that in all positions of the machine without undue friction. The opposite end of the lever 87 is provided with a slot, 88, to engage a pin, 89, which projects from the under side of a slide-bar, 90. This bar 90 is fitted to slide in bearings on the under side of the table, and is rigidly connected with a rack-bar, 51, by a post, 91. The said rack-bar 51 is fitted to slide in the knotter-frame 52, and is connected with one portion of 100 the cam J^5 by a rod, 50, to which it is jointed. The knotter-frame 52 is secured to the binding-table by depending posts 53. The rack of teeth on the bar 51 engage the teeth of the pinion 70, which is mounted to revolve freely on 105 the vertical shaft 63 of the looper. This shaft 63 is notched at 73, Fig. 12, and the pinion 70 is provided with a pawl, 71, impelled by a spring, 72, to bear upon the shaft 63, so that when the pinion is revolved backward in the 110 reciprocating motion of the rack the pawl 71 will drag over the notch 73, but when revolved forward the pawl engages the notch and revolves the looper-shaft.

66 is a nut screwed upon the shaft 63, and 115 further secured thereto by a pin, 67. The upper portion of the nut 66 is cylindrical, and provided with a notch, 68, at one side, into which the rounded nib of a spring, 69, enters, to prevent the looper from being revolved by 120 friction and to hold it set with its jaw 75 in position to begin service. The nib of spring 69 is sufficiently rounded to ride out of the notch in the nut 66 when force is applied to 125 revolve the latter.

74 is the head of the looper neatly rounded, to allow a loop to slide off from it when formed, and slotted vertically to receive the jaw 75, which is journaled therein to oscillate on a pin, 130 L. This jaw is provided with an arc of teeth on its heel to engage a rack, 64, whose stem extends down within the hollow shaft 63, which is vertically slotted to allow the passage of a pin, 62, which connects the rack 64 with a cir-

cumferentially-grooved ring, 61, which is fitted to slide longitudinally upon the shaft 63, whereby the rack 64 is reciprocated, first opening the jaw 75, as shown in Fig. 14, and after 5 a time closing it into the looper-head, as shown in Figs. 10 and 16. This intermittent motion of the ring 61 is produced by the sliding rack 51 through the mediation of a ledge, 54, which is secured to depend from the rack 51, and terminates forward in a rising wedge and rearward in a depressing wedge, aided by a returning-spring, 57.

56 is a shifter, pivoted at its forward end to a stud, *b*, which is fixed to the frame 52, bifurcated at its rear end, and provided with two pins projecting inward to engage the groove in the ring 61.

55 is a shoe, pivoted near its middle to one side of the shifter 56, between flanges 60 thereon, to limit its motion, and its ends are wedge-shaped in opposition to the wedge ends of the ledge 54, whereby the ledge in its forward movement engages the under side of the shoe 55, and with it raises the shifter 56, ring 61, 25 and rack 64, opening the jaw 75, and so holding the said parts while the length of the ledge 54 slides beneath the shoe 55. When the ledge passes the shoe, a spring, 57, Fig. 3, secured to the frame 52 and acting on the shifter 56, 30 presses it down, returning all parts to place. The ledge 54 in its rearward movement passes over the shoe 55 without affecting the latter, unless it chances to be stopped part way; then the ledge will press the shoe home.

35 58 is a pin projecting from the pivot of the shoe, and 59 is a spring secured to the shifter 56, and bearing on the pin to depress the forward end of the shoe to insure its being passed over by the returning-ledge 54. In order to 40 complete the knot with this tyer, the sheaf must be vigorously pushed away from the looper at a given time, to accomplish which I provide arms 108, Fig. 1, fixed at one end of each upon a rock-shaft, 107, which is journaled in arms 45 105, which are fixed upon the needle-shaft *H*², and shaped at its forward end with a curved portion, 106, extending nearly half-way around the needle-shaft, on the end of which curved portion is a friction-roller adapted to be engaged by a curved bar, 104, on being brought into the path thereof by the descent of the needle.

109, Fig. 7, represents a spring upon the rock-shaft 107, acting between the needle-shaft *H*² and the said rock-shaft to hold the arm 106 at rest on the needle-shaft, whereby the arms 108 are held in a plane nearly coincident with the general radial plane of the needle-arm.

50 The curved bar 104 is pivoted at its lower end to a lever, 103, which is pivoted midway to a stud, *d*, that is a fixture of the frame, and the lower end of the said lever 103 is pivoted to the rack-bar 51. In the latter part of the forward motion of the rack-bar it causes the curved bar 104 to engage the roller on the end of arm 106, and rocks the shaft 107 and arms 108 down-

ward and outward against the strain of the spring 109, whereby the arms 108 thrust the sheaf outward upon the table. While the needle *H* descends from the position shown in dotted lines, Fig. 8, to the position shown in full lines, the ejector-arms 108 are moved passively therewith, bringing the arm 106 into the path of the curved bar or cam 104. The return movement of the needle does not affect the ejector-arms. They, being engaged by the bar 104 acting on the arm 106, are forced outward, carrying the bundle onto the drop-leaf 99 of the table. When the bar 104 passes the arm 106, it is set free, and the ejector-arms are returned to their normal position by the spring 109, the arm 106 resting on the shaft *H*². At this time the knife-blade 93 is brought forward and cuts the twine. The blade is pivoted between lugs 92 of the slide-bar 90, in order that it may be swung from its plane of motion by the jaw 75 as it revolves into contact therewith, and the said blade is restored to its normally-vertical position by a spring, 94, which is secured at one end to the bar 90 and presses at its other end against the side of the blade. The slide-bar 90 not only revolves the crown-wheel 80 to catch the twine, and carries the blade 93 to cut the twine, but it tilts a portion of the binding-table at the right time to drop the bound sheaf. The outer portion, 99, is attached to the portion *E* of the binding-table by hinges 100, and it is constantly pressed up into a horizontal position by a spring, 102, 100 which is coiled around the hinge-rod 98, one end of the spring resting against the under side of the part *E* and the other end acting against under side of the movable part 99.

97 is an arm mounted to swing upward freely 105 on the rod 98, but engaging a shoulder on a collar, *e*, which is fixed to the rod, when swung downward beyond a given point.

96 is a plate having a curved wedge-shaped edge, 112, to engage the roller 101 on the end 110 of the arm 97. The plate 96 is supported on an arm, 95, which projects horizontally from the post 91, that connects the bars 90 and 51. The plate 96, in moving forward with the bar 51, engages its edge 113 with the roller 101 115 and swings the arm 97 upward and outward out of its path. The binding being completed, the bar 51 returns to its normal position, and in so doing engages the wedging-edge 112 of the plate 96 with the roller 101, causing arm 120 97 to engage the shoulder on the collar *e*, thereby twisting the rod 98 to tip the portion 99 of the table down to drop the bundle. After the passage of the plate 96, the spring 102 returns the portion 99 of the table to its normal position.

33, Fig. 1, represents an arm fixed upon the shaft 31, and 34 is a spring-latch adapted to catch the arm 33 when the shifter 35 throws the clutch *K*³ into engagement with the drive-cam *J*⁴, and hold the clutch engaged throughout one revolution of the cam, whereby every working part once does duty and returns to place. Now a stud, 39, fixed on rod *J*⁴, trips

the latch 34, leaving the arm 33 free, so that the weight of the crank 30 or a spring will disengage the clutch and stop the binder from working.

5 Operation: The twine being placed in the needle, as described, and its end caught with the crown-wheel I and clamp I' by hand, the machine is to be started. A gavel of grain gathering upon the platform E raises the fingers 29 and the crank 30, engaging the clutch K' with the cam J' and the arm 33 with the latch 34. The cam J', operating through the rod J⁴, lever J³, rock-shaft J', cam-lever J, arm H⁴, needle-shaft H², and needle H, brings a bight of the twine F alongside its first end and both parts of the twine beside the looper-head 74. Now the ledge 54, acting through the shoe 55, shifter 56, ring 61, pin 62, and rack 64, opens the jaw 75, as in Figs. 14 and 15, bending the twine downward beneath it. Now the rack-bar 51, turning pinion 70, brings the pawl 71 to engage shaft 63 at notch 73, and gives a revolution to the knotter 74, and with it the hook 75, in the direction of the arrows. 10 In revolving, the toe 76 of the hook passes under the two parts of the twine and wedges them over the hook 77, forming a double loop around the head, as shown in Fig. 14 and 15. Now the ledge 54 passes from under the shoe 55, the spring 57 throws down the shifter 56, the collar 61, and rack 64, thereby returning the jaw 75 into the head 74, carrying with it the two parts of the twine beneath the heel 77 of the hook, as in Fig. 16, and holding the 15 twine between the sides of the hook 77 and the cheeks of the head 74. Now the crown-wheel I is rotated one notch, taking a new hold of the twine at the needle and carrying it into the clamp I'. Now the knife 93 cuts the two 20 parts of the twine between the clamp and the looper, leaving the two ends of the twine held in the looper. Now the arms 108 are actuated to force the sheaf back on the table, thereby pulling the ends of the twine held by the heel 25 77 through the loop, and the force required to disengage the said ends from beneath the said heel by direct pulling draws the knot tightly. Now the portion, 99, of the table operated 30 through the agency of the arm 97 and wedge-plate 96 swings down and drops the bound sheaf. Then the various parts are returned 35 automatically, as described, to receive another gavel of grain. A short piece of twine is cut off at each operation, and is gradually carried 40 by the crown-wheel through the clamp and dropped. The groove in the back of the needle both guides the twine to the needle's eye and shields the twine from entanglement with the grain, and the outward curve of the needle's 45 radial arm keeps the twine drawn close into the groove.

What I claim as my invention, and desire to secure by Letters Patent, is—

1. In a self-binding harvester, the combination of binding-table E, posts H³, rising therefrom at each end, a shaft, H², journaled in the said posts above the table, a curved needle, H,

secured at one end upon the said shaft, an arm, H⁴, projecting from the shaft, the curved cam-lever J, to engage the arm H⁴, the pendent arm J³, the rock-shaft J', journaled in fixed attachments of the frame and carrying the cam-lever J and arm J³, the cam J⁵, loosely mounted on a shaft, K, driven from the driving-gear of the machine, and means for intermittently connecting the said cam with the said shaft, and a rod, J⁶, connecting the arm J³ with the cam J⁵, substantially as shown and described. 7c

2. The combination of a needle, H, a shaft, H², therefor, journaled in bearings, an arm, H⁴, projecting radially from the shaft, a curved cam-lever, J, to engage the arm H⁴, a rock-shaft, J', to carry the cam-lever, journaled in attachments of the frame at right angles to the shaft H², and means for intermittently rocking the shaft J, substantially as shown and described. 80

3. The combination of a binding-table, a crown-wheel pivoted to the under side thereof and provided with a circle of ratchet-teeth, 90 80, a spring-jawed clamp, I', astride the scalloped edge of the said crown-wheel and secured to the table, a slide-bar, 90, and means for intermittently reciprocating the same longitudinally, a pin, 89, projecting from the 95 slide-bar, a lever, 87, pivoted midway to the table, and having a slot, 88, in one end to engage the pin 89, and a pawl, 83, pivoted midway its length to the other end, the said pawl provided with a roller, 84, in its rear end, and 100 adapted to engage its forward end with the said ratchet-teeth 80, a plate, 85, pivoted at one end to the table, and a spring, 86, secured to the table to press the plate 85 against the roller 84, substantially as shown and described. 105

4. The combination of the crown-wheel I, provided with the ratchet-wheel 80, the detent 81, and spring 82, the pivoted lever 87 and means for oscillating the same, the pawl 83, pivoted midway its length to the said lever, 110 to engage at one end the said ratchet-wheel, and provided with a roller, 84, at the other end, the plate 85, pivoted at one end to engage the said roller along its other or free end, and a spring, 86, actuating the plate to follow 115 the motions of and press constantly upon the said roller, substantially as shown and described.

5. The combination of the cam K' and means for revolving the same, a binding-table, E, the 120 knotter-frame 52, depending from the said table, a looper comprising a head, 74, and means for engaging the twine, a shaft, 63, journaled in the pendent frame 52, a spur-wheel, 70, on the said shaft, and a rack, 51, engaging the 125 said spur-wheel, fitted to slide in the pendent frame, and connected by hinged rod 50 with the said cam, substantially as shown and described.

6. The combination, with a binder-table, E, 130 a knotter-frame, 52, depending therefrom, a knotter, substantially as described, journaled in the said frame, a pinion, 70, on the knotter-shaft, a crown-wheel, I, provided with a

ratchet-wheel, 80, and journaled to the lower side of the said table, a spring saddle or clamp, I', engaging the scalloped edge of the crown-wheel and secured to the table, a rack-bar, 51, 5 engaging the knotter-pinion 70, and connected with reciprocating mechanism, a slide-bar, 90, rigidly secured to the rack-bar 51, and a spring-pawl, 83, engaging the ratchet-wheel 80 and connected with the slide-bar 90, substantially as shown and described.

7. The combination of the knotter-frame 52, the knotter described, having the hollow slotted shaft 63, with the jaw 75, and rack and stem 64, the grooved ring 61, loosely fitted thereon, the pin 62, connecting the said rack and ring, the forked lever 56, pivoted to the said frame and engaging the ring 61, the shoe 55, pivoted to the side of the lever and having oppositely-wedging ends, and the ledge 54, 20 also having oppositely-wedging ends, a bar, 51, carrying the ledge 54 in a path to engage the shoe 55, and means for reciprocating the bar, substantially as shown and described.

8. The combination of the sliding bar 51, 25 the ledge 54, depending therefrom, the pivoted lever 56, having the flanges 60 on one side, and the shoe 55, pivoted to swing between the said flanges.

9. The combination of the sliding bar 51, 30 the ledge 54, depending therefrom, the pivoted lever 56, having the flanges 60, the shoe 55, pivoted between the flanges upon a pin extending through one arm of the lever 56, a pin, 58, projecting laterally from the said pivot-pin, and a spring, 59, secured at one end to the lever 56, and acting at the other end on the pin 58, substantially as shown and described.

10. The combination of the needle-shaft H' and its supports, the rock-shaft 107, journaled 40 in projections 105 on the needle-shaft, and provided with the curved arm 106 and a series of arms, 108, the spring 109, acting to raise the arms 108, the reciprocating bar 51, the lever 103, pivoted midway to a fixed stud, 45 d, also pivoted at one end to the bar 51, and a curved bar, 104, pivoted to the other end of the lever 103, to engage the end of arm 106, substantially as shown and described.

11. The combination of the reciprocating 50 bar 90, having lugs 92, the blade 93, pivoted

between the said lugs to swing sidewise out of its path, and the spring 94, secured to the bar 90 and acting on the blade to restore it to a vertical position, substantially as shown and described.

12. The combination of a binding-table having two portions, E and 99, connected by hinges 100, and a hinge-rod, 98, secured to the one portion of the table, a spring, 102, around the rod and pressing its ends against the under sides of the said two portions of the table, a shouldered collar, e, fixed upon the hinge-rod, an arm, 97, loosely mounted on the said rod and provided with a shoulder to engage the said shouldered collar, and with an anti-friction roller, 101, and a curved wedge-shaped plate, 96, mounted on the slide-rod 90 by means of the depending post 91 and lateral arm 95, substantially as shown and described. 70

13. The combination of the table, made in two parts, hinged together as described, and having the hinge-rod 78 fixed to the free portion of the table, and the spring 102 on the said rod, the shouldered collar e, fixed on the said rod, the arm 97, hung upon the said rod to swing upward freely, and provided with a shoulder to engage the said shouldered collar in its downward motion, and the curved plate 96, mounted on reciprocating mechanism, to move in the path to engage the said arm 97, substantially as shown and described. 75

14. The combination, with the constantly-revolving shaft, of the cam J', the clutch K', adapted to engage therewith, the rock-shaft 31 85 and means whereby the increase of the gavel will rock it, the shifter-arm 35, hung rigidly to the said shaft 31, to engage the clutch K', the arm 33, rigidly hung midway upon the rock-shaft 31, the latch 34, adapted to catch 90 the arm 33, the rod J', connected with the cam J', and the stud 39, fixed to the rod J', to engage the latch 34, substantially as shown and described.

In testimony whereof I affix my signature 95 in presence of two witnesses.

GEORGE WILSON BLAKESLEE.
